CLAIM

The ornamental design for a folding hand-held accupressure massager, as shown and described.

DESCRIPTION

FIG. 1 is an elevational side view of a folding hand-held accupressure massager showing my new design, the view from the opposite side being a mirror image;

FIG. 2 is an elevational front view thereof;

FIG. 3 is an elevational back view thereof;

FIG. 4 is a top plan view thereof;

FIG. 5 is a perspective view thereof; and,

FIG. 6 is a bottom plan view thereof.
